MOWER HOUSING

Leonard B. Goodall, Warrensburg, Mo., assignor to Goodall Equipment, Inc., Minneapolis, Minn., a corporation of Minnesota

Application June 15, 1956, Serial No. 41,903

Term of patent 14 years

(Cl. D40—1)

ing, showing my new design; and

The essential features of the mower housing reside in the portions shown in full lines.

I claim:

The ornamental design for a mower housing, as shown and described.
